TORQUE-CONVERTER CLUTCH

Stephen J. Hoff, Richmond, Ind., assignor to
Hoffco, Inc., Richmond, Ind.

Filed Oct. 6, 1972, Ser. No. 295,514

Term of patent 14 years

U.S. CL. D55—1 G Int. Cl. D15—01

Fig. 4

Fig. 5

FIG. 1 is a perspective view of the torque-converter clutch showing my new design, with the clutch in normal open position;

FIGS. 2 and 3 are opposite end views of the said clutch;

FIG. 4 is a side elevation of the clutch in normal open position; and

FIG. 5 is a side elevation of the clutch in closed position.

I claim:

The ornamental design for a torque-converter clutch, as shown and described.
